UNITED STATES PATENT OFFICE.

WILLIAM E. CONCANNON, OF KANSAS CITY, MISSOURI, ASSIGNOR OF ONE-HALF TO
THOMAS G. CONCANNON, OF EMPORIA, KANSAS.

VALVE-OPERATING MECHANISM.

Application filed September 12, 1923. Serial No. 662,196.

To all whom it may concern:

Be it known that I, WILLIAM E. CONCANNON, a citizen of the United States, residing at Kansas City, in the county of Jackson and State of Missouri, have invented certain new and useful Improvements in Valve-Operating Mechanism; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 This invention relates to a thermostat for controlling the effective port openings of fluid conduits so that the effective port area may be closed, opened or varied in response to temperature.

20 The invention is primarily designed to vary the effective port area or throttle for feeding fuel to internal combustion engines and in its preferred embodiment it is shown as applied in connection with the needle

25 valve of a motor vehicle carburetor such as is now made by the Ford Motor Company of Detroit, Michigan, although I do not wish to be limited to any particular application of my invention, the novelty rather being in

30 the broad application of the device, so while I will hereinafter specifically describe the parts in detail, I would have it understood the changes in form, proportion and minor details of construction may be resorted to

35 without departing from the spirit of my invention or sacrificing any of its advantages.

Fig. 1 is an elevational view of a thermostat applied to the manifold of an internal combustion engine, parts being broken away to illustrate the expansible elements.

Fig. 2 is a view through the needle valve operating mechanism carried by the extension on the end of the thermostat block.

Fig. 3 is a cross sectional view through the thermostat block and through a clamping member applied to an intake manifold, the intake manifold being also shown in section.

Fig. 4 is a detailed perspective view of one end of a thermostatic lever.

50 Fig. 5 is a fragmentary view partly in elevation and partly in section through one end of a thermostatic element.

Fig. 6 is a fragmentary view of two thermostatic elements, a swinging finger and a

55 movement compounding lever.

Fig. 7 is a detailed perspective view of a slightly modified form of thermostat.

Fig. 8 is a fragmentary view of a modified form of stop for one of the thermostatic elements.

Fig. 9 is a sectional view through the bearing block which carries the pinion for operating the needle valve.

In the preferred form of my invention, I employ a heat conducting block 1 which may be of an appropriate construction and which may be held in intimate contact with the intake manifold 2 of an internal combustion engine by a single clamping bolt 3 passing through a clamping member 4 bearing against the manifold and which may be drawn tightly against the intake manifold 2 and against the exhaust manifold 2' by the bolt 3 and the nut 5 so that the block 1 will be maintained in intimate contact with the manifolds. The block is provided with curved faces 6 and 7 so it will lie close to the manifold 2 and conduct heat from the exhaust manifold to the intake manifold. The block is shown as provided with two longitudinal elongated openings or seats 8 and 9 in which are located two expansible members or rods 10 and 11. These members are adapted to expand or "grow" longitudinally under the action of heat due to the fact that they have a high co-efficient of expansion. The member 10 has one end abutting against a stop 12, the other end bearing against a pivoted finger 13, the toe of which bears against a lever 14, pivoted to the block at 15, one end of the lever 14 being provided with a seat 16 to receive the end of the expansible element 11, the opposite end of the expansible element 11 bears against the finger 17 of a rock shaft 18

80 mounted in the block 1 and in the bracket 19, fastened to the block 1. The ends of the expansible element are provided with hardened ends 20 to eliminate the tendency to wear and in the event wear does take place the new contacting ends or screws can be substituted for the worn ones. The rock shaft 18 carries a depending lever arm 21 to the lower end of which is pivoted a flat link 22, also engaging a rack bar 23 meshing with pinion teeth 24 on the sleeve 25 which is fastened to the stem 26 of the valve operator 27, the portion 28 of the stem being flexible so that when the carburetor 29 heats up tending to move the carburetor needle

110

valve 30 out of alignment with portion 26 of the stem of the fork 27, the flexible portion 28 will compensate for the mis-alignment. The sleeve 25 is rotatably secured in 5 a block 31 through which two adjusting bolts 32 and 33 project. The bolts 32 and 33 are hollow bolts or sleeves which are in threaded engagement with the block 31 and which bear against washers 35, in frictional 10 engagement with the extension 36 on the block 1. The bolts 37 extend through the bolts 32 and 33 and have heads 38 overlapping the slot 39 in the extension 36 through which the bolts 37 project. The outer ends 15 of the sleeve bolts 32 and 33 have collars 40 against which the nuts 41 on the threaded ends 42 of the bolts 37 engage. Therefore when the nuts 41 are tightened the block 31 is clamped to the extension 36 by the sleeve 20 bolts, the washers 35 and the head 38 on the bolts 37. By this arrangement the longitudinal adjustment of the block 1 may be made from the front side of the extension 36 which is a very convenient method of 25 making the adjustment. The lever arm 21 is normally urged in one position by a tension spring 43, one end of which engages the ear 44 on the lever 21 and the other which is anchored to the block 1 as at 45, the 30 thermostatic elements 10 and 11 tend to urge the lever arm 21 in a direction opposite to that urged by the spring 43. When the parts are assembled as shown in Fig. 1 the 35 needle valve for the carbureter 29 will initially be open to admit the maximum amount of gasoline to the intake manifold for which the valve is set. As the intake manifold heats up the heat will be communicated to the block 1 in intimate contact with the 40 intake manifold 2 and as this heat is communicated to the thermostatic element 10 and 11 they will expand longitudinally. The element 10 will expand against the finger 13 and since the toe of the lever is 45 near the pivot 15 the end of the lever 14 carrying the seat 16 will move through a greater arc than its opposite end so as to tend to move the thermostatic element 11 from left to right, whereas the thermostatic 50 element 10 expands from right to left and since the thermostatic element 11 will also expand under the influence of heat, a compound leverage or multiplying motion will be provided against the finger 17 so as to 55 swing the lever on 21. Since the finger or projection 17 is a relatively short finger and since the arm 21 is a relatively long arm, it will be apparent that the result of the compounding leverage will be that a relatively slight movement of the thermostatic 60 element 10 and the thermostatic element 11 will impart a relatively large motion or movement to the rack 23, therefore the regulating device will be quite sensitive because 65 slight variations in temperature of the block

1 will cause variations in the effective port area closed by the needle valve 30. The needle valve 30 is illustrated as a conventional form of carbureter needle valve and it is engaged by the forked member 27 so that when the pinion 24 is rotated the stem for needle valve 30 will be rotated. I am aware that hot points, "stoves" and similar devices have been employed prior to my invention for regulating the quantity of gasoline admitted to the intake manifold so I do not claim such a construction in its broadest sense. My invention resides more particularly in the certain refinements which make for efficiency, inexpensive manufacture and in surety of operation. The invention has heretofore been described more particularly to motor vehicles but the same principle with the attendant advantages may be utilized in connection with locomotive steam boilers. Locomotive steam boilers frequently explode due to the fact that the water in the boiler gets low, while the crown sheet gets hot above the water line, then as there is a sudden surge of water against the crown sheet the crown sheet acts as a flash boiler building up the pressure suddenly and causing an explosion. With slight modifications my invention is adapted to eliminate possibility of explosion and I have shown a modified form in Fig. 7 consisting of the block 46 in which are thermostatic elements 47 and 48, one end of the thermostatic element 47 abuts against the stop 49, the opposite end being adapted to contact with the lever 50 pivoted at 51 and having an end 52 to act as a movable stop for the element 48, one end of the movable element 48 bears against a finger 53 on the rock shaft 54, the rock shaft 54 carries an arm 55 corresponding to the arm 21 and it is urged in one position by a spring 56, the lower end of the arm 55 may be connected to a valve for exhausting steam from the boiler in the fire box so as to snuff out the fire. The block 54 will be secured in an appropriate manner to the crown sheet so when the crown sheet becomes too hot the thermostatic mechanism will operate to snuff out the fire in the fire box and thus prevent an explosion.

In Fig. 8 I have shown a modified form of stop arrangement in which a screw 57 is rotated in the end of the block 1, so that the end of the thermostatic element 10 or 47 as the case may be can abut against it instead of against the stop 12 or 49. It will be apparent from the foregoing that the device may be applied to an existing type of engine without materially altering its construction and it is also adapted to be used in connection with locomotive boilers if desired.

By providing the adjustable stop 57, it will be apparent that the device can be set to operate at different temperatures.

What I claim and desire to secure by Letters-Patent is :

1. In a device of the class described, a plurality of parallel co-operating longitudinally expansible thermostatic elements having movement compounding means between them and valve actuating mechanism actuated by said elements, said valve actuating mechanism comprising a bracket, a pivoted lever arm on the bracket having an offset bearing against one end of one of the expansible thermostatic elements, a link connected to the lever arm, a spring connected to the lever arm and anchored at one end, a rack connected to the link, a laterally adjustable bracket, a stem mounted in the bracket, a pinion on the stem engaging the rack and means on the stem for engagement with the needle valve of a carburetor. 55
2. In a device of the class described, the combination of a block, means for attaching the block to the exhaust manifold of an internal combustion engine, a plurality of parallel co-operating longitudinally expansible thermostatic elements having movement compounding means between them, a pivoted lever arm having an offset bearing against one end of one of the longitudinally 60 expansible thermostatic elements, a slotted bracket member carried by the block, a block longitudinally adjustable in the slotted bracket member, a pinion mounted in the block, a stem carried thereby, a rack engaging the pinion receiving its motion from the lever arm and means on the stem for engagement with the needle valve of a carburetor. 65
3. In a device of the class described, a
- block having means for attachment to the exhaust manifold of an internal combustion engine, longitudinally expansible thermostatic means carried by the block, a lever arm pivoted to the block having an offset engageable by the thermostatic means to move the lever arm in one direction, a spring for retracting the lever arm in the opposite direction, a link carried by the lower end of the lever arm, a rack connected to the link, a slotted bracket member carried by the block, a block laterally adjustable in the slotted bracket member, a stem in the block having a pinion engaging the rack and means on the stem for engagement with the needle valve of a carburetor. 70
4. In a device of the class described, a block, means for attaching the block to the exhaust manifold of an internal combustion engine, thermostatic means carried by the block, a rotatable stem, means for transmitting motion from the thermostatic means to the stem, a slotted bracket member on the block, a second block supporting the stem, threaded sleeves passing through the block and binding against the slotted bracket member, the bores of the sleeves being in line with the slot, bolts having their heads bearing against the back face of the bracket member with their threaded ends projecting through the forward ends of the sleeve, and nuts on the threaded ends of the bolts, the sleeves having polygonal portions adjacent to the nuts so that adjustment of the sleeves and bolts may be made from the front side of the bracket member. 75

In testimony whereof I affix my signature.

WILLIAM E. CONCANNON.
